Primary Examiner — Sandra Snapp(74) *Attorney, Agent, or Firm* — Betts, Patterson & Mines, P.S.(57) **CLAIM**

The ornamental design for a massage tool, as shown and described.

DESCRIPTION

FIG. 1 is a top plan view that illustrates the design of the massage tool;

FIG. 2 is a front elevation view thereof;

FIG. 3 is a bottom plan view thereof;

FIG. 4 is a rear elevation view thereof;

FIG. 5 is a left side elevation view thereof; and,

FIG. 6 is a right side elevation view thereof.

The broken lines shown in the drawings form no part of the claimed design.

1 Claim, 3 Drawing Sheets(56)
